UNITED STATES PATENT OFFICE.

GEORGE WILLIAM MASCORD, OF LONDON, ENGLAND.

PRINTING MACHINE.

1,410,824.

Specification of Letters Patent. Patented Mar. 28, 1922.

Application filed May 5, 1920. Serial No. 379,134.

To all whom it may concern:

Be it known that I, GEORGE WILLIAM MASCORD, a subject of the King of Great Britain and Ireland, residing at 14 Castelnau, 5 Barnes, London, S. W., England, have invented certain new and useful Improvements Relating to Printing Machines, (for which I have filed an application in Great Britain Sept. 23, 1918, No. 15,452,) of which 10 the following is a specification.

This invention relates to intaglio printing and has for its object to provide simple and effective means for varying the character or appearance of the printed work or matter 15 whether pictorial or text in the application of ink to the intaglio printing cylinder and in such a manner as to secure effective impressions.

The ink may be applied upon the intaglio 20 engraved cylinder either by a roller revolving in the ink supply and fountain and against the intaglio engraved cylinder, or by spraying on the surface of the intaglio cylinder from a common supply, the super- 25 fluous ink being afterwards removed by a scraper or doctor blade in the usual manner.

According to the invention jets of heated air are applied upon the intaglio cylinder 30 after inking and scraping or cleaning and before the impression is taken. The air is advantageously heated to a temperature of from 80 to 100° F. more or less according to the speed of running. The air is heated by passing over or between electric resistance 35 elements or by other means to ensure precision in the application of heat and the air is passed through a filtering medium for the interception of dust or other foreign matter.

The invention is illustrated by way of example in the accompanying drawings in 40 which—

Figure 1 is a plan,

Figure 2 a front elevation, and

Figure 3 a side elevation of an apparatus 45 adapted to carry out the purpose of the invention.

As illustrated in the accompanying drawings air for the purpose of spraying on to the intaglio cylinder is derived from a fan *f*, 50 by which air is forced through a casing *i* within which an electric resistance heater is mounted so that on the passage of air there-

through it is heated from 80° upwards and thence passes through an air filter *j* and thence into a pipe *k* leading to each end of 55 a tubular casing *l* extending parallel to and above the printing couple. A series of air inlet nozzles *a* are mounted upon a tube or rod *g* extending across the machine in a position adjacent the intaglio printing cylinder *e* and air is supplied thereto through the casing *l* by means of flexible tubes *d*, connected to the casing by unions which may be provided with stop valves to permit closure of any union not required for use. The air 60 inlet nozzles *a* are provided with regulating valves by means of which the supply of air passing through the nozzles may be regulated by means of valve spindles such as *a*². The respective air nozzles may be arranged 65 together in groups for the purpose of regulation so that where only a part of the cylinder is being used that part alone may be sprayed, or again the base or tube carrying the jet nozzles may be subjected to reciprocation, or more than one series of jet nozzles 70 may be employed disposed in different positions with reference to the circumference of the intaglio cylinder.

The ink retained within the intaglio cavities on the cylinder may thus be dried more or less upon its surface as required by the taste or judgment of the operator before the actual printing or impression contact is made, by directing a jet of air in the manner described or a number of jets of air on to any particular portion of the engraved 75 surface desired.

It will be understood that by such means the effect of the printing quality or value of 80 the ink left in the intaglio cavities or recesses of the cylinder may be regulated at will and that also by such means and when running at high speed the printed impression can 85 thus be varied in density, tone, cleanliness, and pictorial value.

I claim:

1. In printing machines adapted for intaglio printing an intaglio printing cylinder, means for spraying heated air upon the intaglio printing surface before impression, said means comprising a series of spraying nozzles and means for independently regulating the discharge of heated air from the 100

said respective spraying nozzles, substantially as described.

2. In printing machines in combination, an intaglio printing cylinder, a fan for supplying air, an air heating device through which the air from the fan is passed, a common casing extending the length of the in-

taglio printing cylinder into which the heated air is passed, and a series of spraying devices connected to the said casing and from which the heated air is discharged upon the intaglio printing cylinder, substantially as described.

GEORGE WILLIAM MASCORD.
